CUT-OFF FOR CIGARETTE MAKING
MACHINES

John Alfred Stein, Richmond Hill, N. Y., assignor to American Machine & Foundry Company, a corporation of New Jersey

Application August 29, 1936, Serial No. 98,529
In Great Britain September 27, 1935

5 Claims. (Cl. 146—101)

This invention relates to cut-offs for cigarette making machines of the continuous rod type, and has for its object to provide an improved and simplified construction of cut-off of the type in which a rotary knife is provided to which an orbital movement is imparted whereby the knife has a movement during the cutting time in the direction of movement of the cigarette rod and which corresponds to or approximates the speed 5 of travel of the cigarette rod.

The invention contemplates the use of a ledger plate of the closed type having a slot to accommodate the knife during the cutting operation which ledger plate also has a reciprocating movement along the axis of the cigarette rod.

The knife may comprise a disc cutter or a narrow blade having an eccentric cutting edge.

According to the invention the orbital movements of the knife are produced by a single crank 20 device and telescopic coupling members are provided between the knife mounting and the ledger plate whereby the ledger plate is reciprocated and the axis horizontal of the knife is maintained parallel to the cigarette rod.

25 The invention consists in a cut-off for a cigarette making machine of the continuous rod type, comprising a rotary knife having a mounting to which orbital movements are imparted by a single crank device, and a ledger plate adapted 30 to reciprocate along the axis of the cigarette rod, and means coupling the knife mounting to the ledger plate whereby the reciprocations of the ledger plate are produced and the knife shaft is maintained parallel to the axis of the cigarette 35 rod.

The coupling means may comprise a pair of rods connected to the knife mounting and engaging sockets on the ledger plate mounting.

In the accompanying drawings:

40 Figure 1 is a front elevation partly in section of a cigarette rod cut off according to the invention.

Figure 2 is a cross sectional elevation through the axis of the crank shaft on line 2—2 of Figure 1.

Figure 3 is a sectional elevation through one of the telescopic coupling members.

Figure 4 is a sectional elevation through the axis of the knife shaft;

50 Figure 5 is a plan view taken on a horizontal plane, indicated in Figure 2 by the section line 5—5, through both of the shafts 10 and 17, as seen in Figure 2.

In carrying the invention into effect according 55 to one convenient mode, a crank shaft 10 is car-

ried in a mounting 11 fixed to the bed 12 of the machine, the shaft lying transversely of the bed having regard to the axis of the cigarette rod. At the rear end of the crank shaft a bevel gear drive 13 is provided from a vertical shaft 14 extending below the bed of the machine.

At its forward end the crank shaft is provided with a crank pin 15 which carries a mounting 16 for the knife shaft 17 through suitable anti-friction bearings. The crank pin 15 is adjustable to the shaft 10 by means of the screw 18 and has also fixed to it a bevel gear 19 which meshes with a bevel pinion 20 on the knife shaft and by which the knife 21 is rotated. The knife 21 is releasably mounted between clamping plates 15 22, 23 of which 22 is keyed to the shaft 17 in known manner. The knife shaft 17 extends at right angles to the crank shaft 10 and is thus parallel to the axis of the cigarette rod. Towards the rear of the knife mounting 16 and located on either side of the axis of the crank pin a pair of sleeves 24 is provided which accommodate a pair of downwardly extending rods or posts 25, such posts being rigidly fixed in the sleeves 24.

25 The posts 25 slidably engage within a pair of socket members 26 carried by a ledger plate mounting 27 which is located below the knife mounting 16. The sockets 26 are inserted within sleeves 28 in the ledger plate mounting and are fixed thereto by the flanges 32 and nuts 29. 30 The posts 25 and sockets 26 form telescopic connections between the knife mounting 16 and the ledger plate mounting 27.

The ledger plate mounting 27 is provided with a pair of guide tubes 30 which slide upon rods 31 fixed in the mounting 11 and lying parallel with the axis of the cigarette rod and in a horizontal plane.

35 The ledger plate 32 is located at one end of its mounting 27 and is provided with a slot 33 to 40 accommodate the knife 21 during cutting.

By the above arrangement it will be appreciated that as the crank shaft 10 rotates an orbital movement will be imparted to the knife mounting 16 and by reason of the telescopic couplings 25, 26 between the knife mounting 16 and the ledger plate mounting 27, the latter will be reciprocated along the rods 31 in accordance with the lateral components of the movement of the knife mounting.

45 At the same time the telescopic couplings 25, 26 maintain the axis of the knife shaft 17 parallel to the axis of the ledger plate and cigarette rod whereby a knife mounting having only a single point of suspension is provided, thus sim- 50 55

plifying the construction and assembly of the parts.

The above mentioned cut-off includes as elements a system of channels L, L', for a lubricant, sealing means M for said lubricant, a knife sharpening device S, a clutch arrangement C, for engagement of the shaft 10 with the gears 13, and means, comprising a screw 18, for mounting the pin 15 upon the shaft 10.

10 I claim:

1. A cut-off for cigarette making machines of the continuous rod type comprising a rotary knife rotatable on an axis parallel to the cigarette rod, a mounting for the knife, a single crank carrying 15 the knife mounting, a ledger plate reciprocable along the axis of the cigarette rod, a mounting for the ledger plate, and vertical telescopic means coupling the mountings together and permitting the knife mounting to approach and recede vertically from the ledger plate mounting, and acting 20 as connections whereby said ledger plate derives a reciprocatory movement exclusively from said single crank.

2. A cut-off for cigarette making machines of 25 the continuous rod type as claimed in claim 1 wherein the ledger plate mounting is supported by, and reciprocates upon, a pair of spaced horizontal rods arranged parallel to the axis of the cigarette rod.

30 3. A cut-off for cigarette making machines of the continuous rod type having means to advance a rod horizontally, comprising a single crank shaft having a crank pin, a mounting for a knife carried upon said crank pin, said knife being 35 rotatable on an axis parallel to the cigarette rod, a ledger plate, a mounting for the ledger plate reciprocable in a direction parallel to the axis of the cigarette rod, telescopic means disposed ver-

tically and coupling the mountings together including a pair of spaced rods carried by one mounting in a plane parallel to the axis of the cigarette rod, and engaging sockets carried by the other mounting, said telescopic means acting as 5 connections whereby said ledger plate derives a reciprocatory movement exclusively from said single crank shaft.

4. A cut-off for cigarette making machines of the continuous rod type having means to advance 10 a rod in a horizontal plane, comprising a single crank shaft having a crank pin, a mounting for a knife carried upon said crank pin, said knife being rotatable on an axis lying in a plane parallel to the plane of the cigarette rod, and spaced 15 above the same, a ledger plate, a mounting for the ledger plate reciprocable in a horizontal plane parallel to the axis of the cigarette rod, vertically located sleeves fixed to the knife mounting on either side of the crank shaft, corresponding vertically arranged sleeves on the ledger plate mounting, and interengaging means carried in said sleeves and forming telescopic couplings between the mountings, acting as connections 20 whereby said ledger plate derives a reciprocatory 25 movement exclusively from said single crank shaft.

5. A cut-off for cigarette making machines of the continuous rod type as claimed in claim 1, wherein the ledger plate has mounting sleeves, and 30 said rotary knife has mounting sleeves, said telescopic means comprising a pair of spaced vertical rods disposed in said last-named sleeves and depending therefrom, and vertical sockets disposed on said ledger plate mounting sleeves, said rods 35 engaging and sliding in said vertical sockets.

JOHN ALFRED STEIN.
